(57) **CLAIM**

The ornamental design for a phone case, as shown and described.

DESCRIPTION

FIG. 1 is a front perspective view of a phone case, showing my new design;

FIG. 2 is a rear perspective view thereof;

FIG. 3 is an exploded front perspective view thereof;

FIG. 4 is a front view thereof;

FIG. 5 is a rear view thereof;

FIG. 6 is a left side view thereof;

FIG. 7 is a right side view thereof;

FIG. 8 is a top plan view thereof;

FIG. 9 is a bottom plan view thereof;

FIG. 10 is a partial enlarged view of portion 10 shown in FIG. 1

FIG. 11 is a partial enlarged view of portion 11 shown in FIG. 3; and,

FIG. 12 is a partial enlarged view of portion 12 shown in FIG. 3.

The dash-dash broken lines illustrate portions of the phone case that form no part of the claimed design. The dot-dash broken line circles in FIGS. 1, 3, 10, 11, and 12 are provided for the purpose of indicating the portion included in the partial enlarged view and form no part of the claimed design.

1 Claim, 12 Drawing Sheets
